Inventor
H. Nagel.

By *John Murphy Jr.* Secretary

UNITED STATES PATENT OFFICE.

HENRY NAGEL, OF NEW ORLEANS, LOUISIANA.

HUMIDIFYING ATTACHMENT.

Application filed May 10, 1922. Serial No. 559,971.

To all whom it may concern:

Be it known that I, HENRY NAGEL, a citizen of the United States, residing at New Orleans, in the parish of Orleans and State 5 of Louisiana, have invented certain new and useful Improvements in a Humidifying Attachment; and I do hereby declare the following to be a full, clear, and exact description of the invention, such as will enable 10 others skilled in the art to which it appertains to make and use the same.

This invention relates to a humidifying or moist air supplying attachment for internal combustion engines and fuel systems.

15 It is aimed to provide a novel efficient and inexpensive means to accomplish the end stated which will effect a substantial saving in fuel.

It is further aimed to provide a construction in which the moist air is admixed with a separate source of air supply, preferably filtered, in order to effectively vaporize the mixture and prevent the use of moisture in too great a quantity in proportion to the air.

25 The invention resides in the novel construction, arrangement and combination of the parts accomplishing the novel result and advantages hereinafter set forth.

One practical embodiment is illustrated in 30 accompanying drawings.

In said drawings:—

Figure 1 is a plan view showing my improvement associated with an internal combustion engine, the latter being fragmentary;

Figure 2 is a side elevation of the parts of Figure 1;

Figure 3 is an end elevation of the parts forming my attachment alone;

40 Figure 4 is a vertical sectional view through the water receptacle taken on the line 4—4 of Figure 1;

Figure 5 is a longitudinal sectional view through the air strainer device; and

45 Figure 6 is a detail perspective view illustrating the means for manipulating the valve employed.

Like reference characters designate like or similar parts in the different views.

50 As the invention is principally though not necessarily, used in connection with internal combustion engines of the vehicle-propelling type, such an engine has been suggested in the drawing as at A of which the intake manifold is designated B. The dash board of

an automobile with which the engine is associated is suggested at C.

In carrying out the invention, a receptacle is provided at 10 adapted to contain water at a predetermined level and to this end being provided with an outlet valve as at 11 which may be opened while the container is filled so that water above said level will drain from the valve 11. After draining, the valve 11 may be closed. This receptacle 60 may be filled in any suitable manner and by way of example may have a filling spout at 12, adapted to be normally closed by a plug closure 13. Said spout 12 is provided at the top wall 14 of the receptacle and secured 65 to said wall 14 is an air intake tube or conduit 15 which extends exteriorly above the wall 14 and which terminates relatively close to the bottom wall of the receptacle and stops below the level of the water therein 70 with its lower terminal portion coiled as at 15a. The wall 14 is provided with an outlet opening surrounded by a nipple at 16 as shown.

The said receptacle or tank 10 may be 80 made of any suitable material for instance, copper. Also, the receptacle 10 may be located wherever desired on the automobile and for instance at the rear of the said dash board C by means of an attaching bracket 17 85 carried by the receptacle and bolted or otherwise fastened at 18 to its support.

In communication with the said intake manifold B is a pipe or conduit 19 having one end in communication with the atmosphere and with the opening at said end covered by an air strainer 20. The air strainer 20 may be of any suitable construction but is preferably of metallic gauze soldered or otherwise secured as at 21 to 90 the adjacent end of conduit 19. Tapped in the conduit 21 is a T-coupling 22 to which a conduit 23 connects and which leads from the nipple 16. This conduit may be of any suitable material but is preferably of a flexible 95 nature and may be rubber tubing preferably slipped over the nipple 16 and the attaching part of the coupling 22. The connection between screen 20 and conduit 19 is considerably smaller than pipe 23 so that 100 pressure will be exerted at the top of tank 10.

Connected in the conduit 19 intermediate the coupling 22 and the manifold B, is a suitable type of throttle valve 25 having an operating stem at 26. As it is desired that 110

the valve 25 may be operated from the driver's seat, the manipulating rod is provided at 27, detachably connected at 28 to the rod 26, and slidably through an appropriate opening 28^a in the dash board C. In front of the dash board, the rod 27 may have a rosette or other manipulating handle 29.

In operation of the engine or motor A, a partial vacuum will be created through 10 the manifold B, the conduit 19, conduit 23 and the tank 10, causing air to be drawn in through the conduit 15 and the water in the tank 10, whereby it will be effectively washed. The air will then be drawn through 15 the conduit 23 and conduit 21. It will be realized that the air thus drawn into the conduit 23 will be vapor-laden or moist and when it discharges into the conduit 21 it will be in that condition. Simultaneously, 20 air is drawn in through the strainer at 20 into conduit 19, intimately admixing with the air discharging into the conduit 21 from the conduit 23 so as to effectively atomize the moisture contained in the air. Such atomized mixture is then drawn into the 25 manifold B through the valve 25. The latter being completely open or appropriately throttled as desired through manipulation of the handle 29. It will be understood that this moist air within the manifold mixes with the carbureted fuel supplied thereto and thus converts it into a leaner mixture. In addition, I have found that the use of 30 this attachment functioning in the manner stated, effects a saving in fuel, and substantially eliminates carbon trouble in the motor.

As merely one practical embodiment has been illustrated and described, it is to be 40 understood that changes in the details may

be resorted to provided they fall within the spirit and scope of the invention.

Having thus described the invention, what I claim is:—

1. In a humidifying attachment, a conduit for communication with the fuel intake means of an internal combustion engine, a water container, a conduit in communication with said conduit and with said container, means on the container communicating with the atmosphere for passage of air through the water and thence through the second mentioned conduit, the second mentioned conduit being in communication with the atmosphere beyond its junction with and at an angle to the first mentioned conduit. 45

2. In a humidifying attachment, a conduit for communication with the fuel intake means of an internal combustion engine, a water container, a conduit in communication with said conduit and with said container, means on the container communicating with the atmosphere for passage of air through the water and thence through the second mentioned conduit, the second mentioned conduit being in communication with the atmosphere beyond its junction with and at an angle to the first mentioned conduit, air straining means at the free end of the 60 second mentioned conduit, and a throttle valve in the first mentioned conduit between the point of connection with the second mentioned conduit and the fuel intake means. 65

In testimony whereof I affix my signature 70 in presence of two witnesses.

HENRY NAGEL.
